FREE-STANDING STOVE

Egbert Howland and Kurt R. Howland, Maryland, N.Y.
(both % American Spinning & Metal Products, Shelter
Rock Road, Danbury, Conn. 06810)

Filed Oct. 17, 1974, Ser. No. 515,508

Term of patent 14 years

Int. Cl. D23—03

U.S. Cl. D23—97

FIG. 1

FIG. 2

FIG. 3

FIG. 4

FIG. 5

FIG. 6

FIG. 1 is a perspective view of a free-standing stove embodying our new design;

FIG. 2 is a front elevational view thereof, the screen pattern which is partially shown is understood to repeat uniformly across the length and width of the circumscribed area;

FIG. 3 is a left side elevational view thereof, the right side being a mirror image;

FIG. 4 is a rear elevational view thereof;

FIG. 5 is a top plan view thereof; and

FIG. 6 is a bottom plan view thereof.

We claim:

The ornamental design for a free-standing stove, substantially as shown and described.
